Filed Apr. 10, 1968, Ser. No. 11,448

Term of patent 14 years

Int. Cl. D9—08

U.S. Cl. D9—252

Part of the bundle tie is shown broken away in FIG. 1 to indicate indeterminate length.

We claim:

The ornamental design for a bundle tie, substantially as shown and described.
